(57) **CLAIM**

The ornamental design for an cassette for dental hand instruments, as shown and described.

DESCRIPTION

Figure 2.1: is a top perspective view of a cassette for hand instruments in a closed position;

Figure 2.2: is a bottom perspective view thereof;

Figure 2.3: is a top perspective view of the cassette for dental hand instruments in an open position;

Figure 2.4: is a cross-sectional view thereof taken along line 2.4 shown in Figure 2.1; and

Figure 2.5: is a bottom perspective view thereof.

The broken lines shown in Figures 2.1-2.5 illustrate portions of the cassette for dental hand instruments that form no part of the claimed design.
